(57) **CLAIM**

The ornamental design for a column soap mold, as shown and described.

DESCRIPTION

FIG. 1 is a front, side isometric view of a column soap mold having an inner tube and an outer casing;

FIG. 2 is a front, side exploded, isometric view of a column soap mold having an inner tube and an outer casing;

FIG. 3 is a front, top isometric view of an inner tube of a column soap mold;

FIG. 4 is a rear, bottom isometric view of an inner tube of a column soap mold;

FIG. 5 is a front view of an inner tube of a column soap mold;

FIG. 6 is a rear view of an inner tube of a column soap mold;

FIG. 7 is a left-side view of an inner tube of a column soap mold;

FIG. 8 is a right-side view of an inner tube of a column soap mold;

FIG. 9 is a bottom view of an inner tube of a column soap mold;

FIG. 10 is a top view of an inner tube of a column soap mold;

FIG. 11 is a front, top isometric view of an outer casing of a column soap mold;

FIG. 12 is a rear, bottom isometric view of an outer casing of a column soap mold;

FIG. 13 is a front view of an outer casing of a column soap mold;

FIG. 14 is a rear view of an outer casing of a column soap mold;

FIG. 15 is a left-side view of an outer casing of a column soap mold;

FIG. 16 is a right-side view of an outer casing of a column soap mold;

FIG. 17 is a top view of an outer casing of a column soap mold; and,

FIG. 18 is a bottom view of an outer casing of a column soap mold.

(Continued)

The claim is directed to the collective appearance of all elements shown. Any shading and cross-hatching are not features of the design but are utilized to illustrate the surface contours of the column soap mold design in the drawings. The dash-dash broken lines depict portions of the column soap mold design that form no part of the claimed design. The dash-elongated dash broken lines depict the bounds of the claim and form no part of the claimed design.

1 Claim, 16 Drawing Sheets
